UNITED STATES PATENT OFFICE.

CASPER BUHRER, OF SANDUSKY, OHIO.

METALLIC RAILWAY-TIE.

SPECIFICATION forming part of Letters Patent No. 702,400, dated June 17, 1902.

Application filed August 7, 1901. Serial No. 71,248. (No model.)

To all whom it may concern:

Be it known that I, CASPER BUHRER, a citizen of the United States, residing at Sandusky, in the county of Erie and State of Ohio, have invented new and useful Improvements in Metallic Railway-Ties, of which the following is a specification.

The object of my invention is the production of a cheap and serviceable metallic railway-tie which can readily be fashioned from new metal or from old and worn track-rails, which shall be provided with anchoring means for holding the same against longitudinal movement in the material or ballast of the road-bed, which shall have holes to receive bolts that secure the track-rails to the same, which shall be adapted to satisfactorily take the place of the wooden tie now in common use, and which, withal, shall constitute a superior means for supporting the track-rails, holding them in place, and forming a stable, smooth, and superior permanent way.

With these main ends in view my invention consists in a metallic tie having a web, top flanges for supporting the track-rails, bottom flanges preferably wider than those at the top, and anchoring means in connection with the lower flanges for holding the tie against the movement.

The accompanying drawings illustrate an example of my improved tie and a modification of the anchoring means.

Figure 1 shows a metallic tie with track-rails secured in position thereupon by suitable means. Fig. 2 is a top plan view of the tie, the central part being removed. Fig. 3 is a bottom plan view of Fig. 2. Fig. 4 is a section of the tie, taken on a line through the anchoring means. Fig. 5 shows an old track-rail, the head being split in accordance with the first step of my method of re-formation. Fig. 6 illustrates in section the tie as it appears after the head has been rolled or fashioned into wide flanges. Figs. 7 and 8 are plan and side views of the clamping-plates. Fig. 9 illustrates a modification of the anchoring means for the tie.

Referring to the several figures, the numeral 1 designates the tie as a whole; 2, the web of the tie, and also of the old track-rail.

3 designates the upper flanges of the tie

extending each side of the web; 4, the lower flanges of the tie preferably of greater width than the top flanges; 5, depressions in the bottom flanges located in this instance some 55 six inches from the ends; 6, holes to receive the bolts which secure the track-rails to the upper flanges of the tie; 7, the track-rails.

8 is an angle-splice of a well-known form. 9 designates clamping-plates for holding 60 the track-rails upon the tie; 10, lips of the clamping-plates; 11, the beveled faces of the lips; 12, surfaces perpendicular to the parallel faces of the plates and which are adapted when the plates are in use to engage the 65 edges of the flanges or base of a rail or the edge of an angle-splice.

13 designates lugs which fit within the recesses made in the edges of the angle-splice to prevent longitudinal movement of the rails. 70

14 designates bolts which pass through the clamping-plates and holes 6 in the tie and are held in position by nuts.

15 designates plates having depressions riveted to the lower flanges of the tie. 75

16 is the head of an old track-rail, and 17 is a longitudinal groove in the head of the rail.

I preferably manufacture my tie from old and worn track-rails somewhat as follows: The old rail is first cut into sections of the 80 proper tie length, which in some cases may be eight feet six inches; secondly, a section is heated to a rolling heat; thirdly, it is next placed in a vise-constructed anvil or the like, which will firmly grip the base and web 85 of the section and form a solid support for the head of the rail; fourthly, the rail is passed longitudinally under a wedge-shaped roll, which will split and roll the head to the approximate shape shown by Fig. 5 of the 90 drawings; fifthly, the head of the rail is then passed under other rolls and fashioned into the shape shown by Fig. 6. Finally, anchoring depressions 5 are pressed in the flanges 4 and preferably adjacent the ends of the rail 95 or tie. As a modification of the last step, I may secure to the flanges 4 specially-constructed plates, which will perform the requisite functions of the depressions that are integral with the lower flanges of the tie.

It is obvious that the base of the rail will be used to receive the track-rails and that

the refashioned head transformed into wide flanges will be located in the ballast of the road-bed.

While I have illustrated and described one example of the physical embodiment of my invention, embracing a modification of the anchoring means, and set forth one specific method or process of manufacturing the tie and that by refashioning the head of an old and worn track-rail, I do not thereby intend to restrict my invention to the exact shape of the tie or to the exact method of manufacture, inasmuch as the shape of the tie may be somewhat changed and the same under some circumstances rolled from new metal, although I prefer to form it from old rails.

What I claim as new, and desire to secure by Letters Patent, is—

1. A metallic railway-tie comprising a single, vertical, integral web, top flanges extending each side of the web and presenting a plain level surface to receive track-rails, bottom flanges extending each side of the web and of greater width than the top flanges, and anchoring means projecting from the under surface of the lower flanges of the tie, and

extending crosswise thereof; the said top flanges adjacent the ends, where they are to receive the flanges or bases of the track-rails, being integral and of the same width as the other portions of the top flanges. 30

2. A metallic railway-tie having a web, top flanges, bottom flanges, and depressions formed in the lower flanges to serve as anchoring means. 35

3. The combination with a metallic railway-tie having a single, vertical, integral web, top flanges with holes each side of the web, bottom flanges, and anchoring means at the lower flanges extending crosswise of the tie 40 and projecting downwardly, of track-rails, perforated clamping-plates; and bolts; the said clamping-plates being located upon the top plain surface of the flanges of the tie and being provided with lips which engage the 45 base of the track-rail.

In testimony whereof I affix my signature in presence of two witnesses.

CASPER BUHRER.
